UNITED STATES PATENT OFFICE.

JOHN ROGER, OF DENVER, COLORADO, ASSIGNOR OF ONE-HALF TO
THOMAS EDWARDS, OF BALLARAT, VICTORIA, AUSTRALIA.

FURNACE-FEEDER.

SPECIFICATION forming part of Letters Patent No. 770,701, dated September 20, 1904.

Application filed January 18, 1904. Serial No. 189,597. (No model.)

To all whom it may concern:

Be it known that I, JOHN ROGER, a subject of the King of Great Britain, residing at Denver, in the county of Denver and State of Colorado, have invented new and useful Improvements in Furnace-Feeders, of which the following is a specification.

This invention relates generally to furnace-feeders, and particularly to one of that class employed in feeding ore to ore-roasting furnaces.

The object of the invention is in a ready, positive, and thoroughly-efficient manner to feed ore or other material to a furnace; to cause the operation to be continuous and automatic and to feed only the requisite amount, thereby avoiding waste and improper treatment of the ore; to obviate wear of the parts, thus to increase the usefulness of the apparatus, and generally to improve apparatus of this description.

With the above and other objects in view, as will appear as the nature of the invention is better understood, the same consists, generally stated, in a novel form of ore-feeding apparatus which is constructed and operates in such manner as to cause positive feed of ore to the hearth or furnace on one movement and on the opposite movement to clear the ore, thus to prevent any waste, as by dragging or pulling the ore out of the furnace. In apparatus of this character it is necessary in order to secure the best and proper results to construct the feeding apparatus in such manner as to reduce danger of breakage or inoperativeness in use to a minimum. This result is of course secured by simplifying the construction of the parts which go to make up the apparatus and at the same time to dispose them in such manner with relation to the furnace as to permit of ready repairs, if necessary.

As will presently appear, all the objects above stated are secured in the present invention in a manner that is at once feasible and practicable and will not necessitate any change in the structural arrangement of an existing furnace to adapt the present improvements thereto.

In the accompanying drawings, forming a

part of this specification, and in which like characters of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in horizontal section of an ore-roasting furnace, exhibiting the apparatus of the present invention operatively connected therewith. Fig. 2 is a view in vertical transverse section showing certain parts omitted in Fig. 1. Fig. 3 is a view in side elevation.

In defining the operations of the ore-feeding mechanism the terms "charging" and "recharging" are employed, the term "charging" meaning the backward movement of the apparatus to receive a fresh charge of ore or the like, and the term "recharging" meaning the forward movement when the apparatus conveys or pushes the ore into the furnace.

The ore-feeding mechanism of the present invention is adapted for use in connection with any style of ore-roasting furnace and in this instance is shown as combined with what is known as the "Edwards" ore-roasting furnace. As the furnace *per se* forms no essential part of the present invention, detailed description of the parts thereof will not be given other than to state that 1 is the shell of the furnace, which may be constructed in any manner; 2, the roasting-hearth; 3, the arch over the hearth which incloses the chamber for the passage of hot gases, as usual, and 4 rabble-arms, which are carried by vertical shafts 5 and perform the functions common to such elements, the shafts 5 being driven from any suitable source of power through the medium of pinions 6, meshing with bevel-gears 7, carried by the shafts 5, the pinions being carried by a shaft 8, driven from any source of power, not necessary to be shown.

The present invention, as before stated, resides in the novel form of mechanism for feeding proper amounts of ore or other material to the roasting-hearth.

Before describing the furnace mechanism it may be stated that a suitable hopper 8^a is disposed at the feed end of the furnace, said hopper being provided with a chute 9, which 5 discharges ore at the proper point within the furnace, to be supplied thereto by the feeding mechanism. There is a gate 10 combined with the chute, by which the amount of ore fed may be regulated at will, and the bottom 10 portion of the hopper may be closed by a cut-off valve 11, carried by an arm 12. In the operation of the machine the valve 11 may be open to permit free passage of ore down the chute and into the furnace, the amount to be 15 supplied to the furnace being determined by the adjustment of the gate 10; but in the event that it is desired suddenly and entirely to cut off the supply of ore or other material to the furnace the valve 11 is closed for this 20 purpose.

The feeding mechanism embodies a rod or bar 13, carrying a plurality of hoes 14, suitably spaced apart, the said hoes when the ore is being fed to the furnace passing close to 25 the bottom of the roasting-hearth; but on the return movement when a fresh supply is to be fed to the furnace the hoes are raised above the ore, thus to prevent any tendency on the part of the feeding apparatus to drag out 30 portions of the ore that would otherwise be contained between the hoes. The rod works in an opening 15, formed in one wall of the furnace, said opening being of the proper size to allow free motion of the hoes without danger of 35 binding. The rod 13 is fulcrumed intermediate of its ends upon a pin or bolt 16, which passes through two bell-crank levers 17, fulcrumed at their upper ends upon a rock-arm 18, the latter being supported upon a shaft 19, working 40 in suitable boxes 20. The rear or outer end of the rod is fulcrumed between the upper ends of two links 21, being held in operative position through the medium of a pin or bolt 22, which passes through the two links 45 and the rod. As shown in Fig. 2, the rock-arm comprises two members, which are spaced apart a sufficient distance to allow the hoe-rod to reciprocate between them, the rock-arm being actuated through a connecting-rod 24, one 50 end of which is connected with a crank-pin 25, carried by a disk 26, mounted on a shaft 27, the said shaft being driven from the shaft 8 through the medium of a pinion 28, carried by the shaft 8, and a gear 29, carried by the shaft 27. The timing of the parts is to be 55 such that there will be no interference between the rabble-arms and the hoe-rod. It will be seen from the arrangement of mechanism that when the disk 26 revolves a reciprocating motion will be imparted to the connecting-rod 24, and this latter will impart a reciprocatory movement to the rock-arm 18, thereby causing the hoe-rod to enter and leave 60 the roasting hearth or furnace, the forward movement of the hoe-rod causing the ore 65

which has been deposited upon the hearth to be moved inward the proper distance to be acted upon properly by the rabble-arms. As before stated, in its forward or feed movement the hoes 14 work in close proximity to 70 the hearth, and thus positively feed all of the ore or dust into the furnace. As before pointed out, it is necessary that the hoe-rod should be lifted on its backward movement to prevent the hoes from dragging the ore 75 and dust out of the furnace, and to effect this result the connecting-rod is provided with a vertical member 30, rising in this instance from the fulcrum 31 of the rod, the upper end of the arm 30 having pivotally connected 80 with it one end of a link 32, the other end of the link being pivotally connected with the lower ends of the bell-crank levers 17, as clearly shown in Fig. 2. The connecting-rod also is provided with a longitudinal extension 33, which projects beyond the fulcrum-point 31 85 and is connected with the lower end of the links 21 at 34.

From the arrangement of mechanism disclosed it will be seen that when the crank-pin 90 25 is turned in the direction of the arrow shown in Fig. 2, under which motion the hoe-rod is projected into the hearth, as the crank-pin passes its forward dead-center the forward end of the connecting-rod will be depressed, thereby projecting the arm 30 toward the furnace and through the link 32 rocking the bell-crank levers 17 in a direction to raise their horizontal members, and thus lift the hoes away from the hearth. When 100 the crank-pin passes its rear dead-center, the forward end of the connecting-arm is raised, thereby swinging the arm 30 away from the furnace and through the medium of the link 32 depressing the horizontal members of the 105 bell-crank levers and causing the hoes to approach the hearth, so that upon the forward movement of the hoe-rod the proper feeding of the ore to the hearth is effected. By the 110 provision of the links 21 the forward end of the hoe-rod is positively held from dropping and is further caused to move in a line parallel with the hearth.

It will be seen from the foregoing description that while the mechanism of this present 115 invention is exceedingly simple in construction it will be found thoroughly efficient and durable in use for the purpose designed and that danger of breakage in use or derangement is reduced to a minimum.

Having thus described the invention, what I claim is—

1. In an apparatus of the class described, an ore-feeding element comprising a body member provided with a plurality of rigid 125 depending blades or hoes, means for actuating successively a downward, forward, upward, and retracting movement of the element, and means for delivering material between the blades. 130

2. In an apparatus of the class described, a rod carrying a plurality of blades or hoes, a rock-arm, bell-crank levers carried by the rock-arm and operatively connected with the rod, a connecting-rod, and a connection between the connecting-rod and one of the arms of the bell-crank levers. 30
3. In an apparatus of the class described, a rod carrying a plurality of blades or hoes, a rock-arm, bell-crank levers pivoted at their bend to the rock-arm, connections between one of each of the arms of the bell-crank levers and the rods, a connecting-rod pivotally connected with the rock-arm, means for reciprocating the connecting-rod, and means for connecting one of the arms of each of the bell-crank levers with a portion of the connecting-rod. 35
4. In an apparatus of the class described, a rod carrying a plurality of blades or hoes, a rock-arm, bell-crank levers carried by the upper portion of the rock-arm and operatively connected with the rod, a connecting-rod pivoted to the rock-arm and provided with a vertical extension, and links connecting the extension with the free arm of the bell-crank lever. 40
5. In an apparatus of the class described, a rod carrying a plurality of blades or hoes, a rock-arm, bell-crank levers carried by the intermediate portion of the rock-arm, a connection between the intermediate portion of the rod and the bell-crank levers, a connecting-rod, and means for reciprocating the same, said rod being provided with a horizontal and a vertical extension, links connecting the vertical extension with the free arms of the bell-crank levers, and links connecting the terminal of the horizontal section with the outer terminal of the hoe-rod. 45
6. An ore-roasting furnace having an opening in one side and a feed-chute communicating therewith, rabble mechanism arranged within the furnace, a rod carrying a plurality of blades or hoes, a rocking arm, bell-crank levers carried by the rocking arm and operatively connected with the rod, a connecting-rod driven by the rabble-actuating mechanism, and a connection between the connecting-rod and one of the arms of the bell-crank levers. 50

In testimony whereof I have hereunto set my hand in presence of two subscribing witnesses.

JOHN ROGER.
